RAZOR BLADE

Zemach Auerbach, New York, N. Y.

Application November 8, 1941, Serial No. 418,339

1 Claim. (Cl. 30—348)

This invention relates to novel safety razor blades of either the thin flexible type or rigid blades.

More particularly, my blade contains a ridge on the razor blade formed from the same material as the blade itself. Such ridge serves to reinforce the blade and to make the blade more rigid, thus passing on that rigidity to the cutting edges of the blade so that it is maintained in a straighter position to give the shaver a better shave.

A further object of my invention is to provide both a ridge and channels in the blade formed from the same material as the blade, the ridge and channels being parallel to one another to give the blade both rigidity and flexibility and in order to provide a better blade for shaving.

The ridge and channels in the blade tend to stiffen the blade and aids in accurately aligning the blade in relation to the guards of a safety razor so that identical cutting edges are presented for shaving. When the flexible blade having the ridge is flexed transversely within the razor, the tendency for the blade to snap or break is greatly reduced and because of the added rigidity to the blade it is possible for the manufacturer to harden the temper of the blade in order to provide cutting edges having greater resistance to the shaver's beard.

A further object of my invention is to provide channels in a blade in conjunction with a ridge so that the blade can be made of heavier steel, at the same time giving the blade flexibility, that is the blade can be transversely flexed when positioned within the razorhead. In a blade of the heavier type a better cutting edge can be given to the blade, at the same time the edge can be maintained in straighter position during the shaving operation, thus giving a better shave.

For a fuller understanding of the nature and objects of my invention reference is had to the

detailed description in accordance with the accompanying drawing, in which:

Fig. 1 is a top view of my blade.

Fig. 2 is a similar view of the blade as seen from the opposite side.

Fig. 3 is an end view of the blade shown in Figs. 1 and 2.

Referring to Figs. 1 to 3, inclusive, numeral 147 represents a blade comprising a rectangular member 148 made of sheet steel with longitudinal cutting edges 149—149, the shorter sides 150—150 being unsharpened. Along the longitudinal medial line on the face of blade 147 there is a longitudinal ridge 151, on either side of longitudinal ridge 151 and in the face of the blade there are a series of parallel channels 152—152, the ridge 151 and channels 152 being formed of the same material as that of the blade. The opposite face 153 of the blade 147 is entirely flat as shown in Fig. 2. The ridge and channels function to locate the blade within a razorhead, the channels providing greater flexibility to the blade during transverse flexing of the blade.

The blade heretofore described can be either of the thin flexible type or of the rigid type and may be made in different proportions than the blade pictured in the drawing.

It is obvious that various changes and modifications may be made in the general details of construction without departing from the spirit of the invention, as set forth in the appended claim:

I claim:

A razor blade having one smooth face and on the other face a ridge along the longitudinal medial line of said blade and a series of longitudinal channels spaced equally distant from the longitudinal medial line of said blade, said channels and said ridge being parallel to one another and formed from the same material as said blade.
